AUTOMATIC RECORD CHANGER

Vaughn Butler, Harriman, Tenn.

Application April 22, 1940, Serial No. 330,879

7 Claims. (Cl. 274—10)

This invention relates generally to record-changing means for a sound-reproducing machine and in particular to a record-changer adapted to automatically change a plurality of records in succession.

In the automatic record changers of the prior art, in which a plurality of unplayed records of disc type are stacked in a position above the turntable, a change of records is usually accomplished by mechanism arranged at the circumference of the record being played and operable to be slipped or positioned between the record to be released for positioning on the turntable and the records remaining in the stack. The satisfactory operation of the releasing mechanism is dependent upon the stacked records being in horizontal alignment at their circumference, to provide for the positioning of the record-releasing elements on opposite sides of the record, the distance or spacing between the elements adapted to effect a separation or release of a record from the stack of unplayed records, being in correspondence with the thickness of the usual disc record. In instances, therefore, where the stack of unplayed records are unevenly spaced, as in the case of warped records or records of an odd thickness, an automatic changing of these records cannot normally be effected so that considerable inconvenience results in the selection of records which are sufficiently flat or of a suitable thickness to be satisfactorily accommodated by the record changing mechanism. The record changers of the prior art, therefore, are generally unreliable in operation.

Furthermore, the record changers of the prior art usually require a rather complicated structure adjacent the circumference of the turntable, for the storage of records and for the shifting of the stored records into a playing position on the turntable. Considerable additional space, apart from that needed for the reproduction mechanism, is thus required within the sound reproducing machine to accommodate the record changing apparatus, whereby the cost and bulk of the machine is unduly increased. Also, these complicated record-changing structures are generally clumsy looking and detract from the appearance of the sound-reproducing machine, particularly those machines in which the turntable is visible at all times.

It is an object of this invention, therefore, to provide an improved automatic record-changer for a sound reproducing machine.

It is a further object of this invention to provide an automatic record changer in which the

mechanism for releasing a record for playing position on the turntable is adapted to engage the record at the central aperture formed therein to provide for reliability of operation in the changing of both warped and flat records.

It is another object of this invention to provide an automatic record changer which is of compact and rugged construction, comprised of a minimum of parts requiring adjustment, and which is readily adapted for use with sound-reproducing machines employing either ten inch or twelve inch records.

It is a further object of this invention to provide a record changer in which records successively dropped into a playing position on the turntable can all be removed at one time from the turntable.

It is a still further object of this invention to provide a record changer adapted for use with either ten inch or twelve inch records, in which a support for supporting the edges of unplayed records stacked above the turntable is adapted to automatically adjust the operation of the tone arm in correspondence with the size of the records being played.

A feature of this invention is found in the provision of a record changer in which only a combination of stationary supports for supporting a stack of records above the turntable are visible on the face of the phonograph or the like, the means for successively releasing the records to a playing position on the turntable being assembled within one of the stationary supports and operable through such support to engage the record to be released at the central aperture formed therein, to in all provide an automatic record changer which is positive in operation, neat in appearance, and of a very simple construction.

Further objects, features and advantages of this invention will be apparent from the following description when taken in connection with the accompanying drawings in which:

Fig. 1 is a plan view of a preferred embodiment of the invention showing the arrangement of the driving system for the automatic record changer;

Fig. 2 is an enlarged sectional view of the turntable spindle showing the record releasing mechanism assembled therein;

Fig. 3 is a view illustrated similarly to Fig. 2 showing the releasing mechanism in changed position;

Fig. 4 is a view partly in section as seen on line 4—4 in Fig. 5;

Fig. 5 is a sectional view taken approximately along the line 5—5 in Fig. 4;

Fig. 6 is a fragmentary sectional view taken on line 6—6 in Fig. 4;

Fig. 6A is an electrical diagram showing the control circuit for the record releasing mechanism shown in Fig. 1.

Fig. 7 is a fragmentary sectional view taken on line 7—7 in Fig. 4;

Fig. 8 is a view illustrated similarly to Fig. 7 showing the parts thereof in a changed position;

Fig. 9 is a developed view of the cam portion enclosed between the lines 9—9 in Fig. 4;

Fig. 10 is a view in perspective of a record retaining member;

Fig. 11 is a plan view of a modified form of the invention showing the arrangement of the driving system for the record changer mechanism;

Fig. 12 is a sectional elevation taken on the line 12—12 in Fig. 11;

Fig. 13 is a bottom elevation of Fig. 11, showing the record changing mechanism, and

Fig. 14 is an elevational view as seen along the lines 14—14 in Figs. 11 and 13.

This invention contemplates the use of disc type records wherein the unplayed records are stacked in a supported position above the turntable of the phonograph or like machine, means being provided for successively releasing the lowermost or bottom record in the stack of unplayed records to provide for its falling into a playing position on the turntable. The invention contemplates further a combination of stationary supports with one of said supports being arranged at the circumference of the turntable and the other of said supports being arranged at the center of said turntable, the center support being provided with record releasing means which are completely retractable within such support and which are operable by cam means located below the turntable to effect a dropping of the lowermost record of the unplayed records from the center and edge supports into a playing position on the turntable. The cam means located below the turntable are operable to raise the tone arm from the record in playing position and to move the tone arm beyond the circumference of such record before actuating the releasing means in the center support to drop the next successive record at the bottom of the stack of records in a playing position on the turntable. The invention is equally adaptable for use with either ten inch or twelve inch records and provides means for automatically adjusting the angular movement of the tone arm in correspondence with the size of the record on the turntable.

There is illustrated in Figs. 1 and 5 the usual cabinet wall 20, turntable 21 and tone arm 22 for a phonograph or like machine. The turntable is driven by a low voltage induction motor 23 which is floatingly supported in a suitable manner from the wall 20, the motor shaft being provided with a pulley 24 which is in frictional engagement with the turntable driving pulley 26 which in turn is in frictional engagement with the table rim 27. A shaft or spindle 28 is secured to the wall 20 in an obvious manner by the clamping action of the shoulder 29 and nut 31 and rotatably supports the turntable, the hub portion of which includes a pulley 32 which is in driving connection with an idler pulley 33 through a flexible spring drive 34. The pulley 33 is mounted at the upper end of a counter

shaft 36 which is rotatably supported in a bushing member 37, the member 37 being suitably secured in the wall 20 as by welding or like means. An idler pulley 38 is fastened to the lower end of the counter shaft 36 by screw means such as 39, the pulley 38 being in driving connection with a pulley 41 which is rotatably mounted at one end of a stub shaft 42; the shaft 42 being mounted in the wall 20 by screw means 43 and the pulley 41 being maintained on the shaft 42 by screw means 44. The pulleys 33 and 38 act as reduction pulleys between the pulleys 32 and 41; with the entire pulley system being in operation concurrently with an operation of the motor 23. A serrated flange 46 formed on the upper side of the pulley 41 provides for a driving engagement of the pulley 41 with an operating cam 47 in a manner to be hereinafter fully described. The cam 47 is rotatably mounted on the stub shaft 42, the bearing assembly 48 between the cam 47 and pulley 41 allowing pulley 41 to rotate independently of the cam 47. The cam 47 (Figs. 4 and 5) is of multiple type and is formed with cam faces 49, 52 and 54, which are operatively associated with cam followers 51, 53 and 56, respectively.

The movement of the cam follower 51 on cam 49 is adapted to provide for a lifting of the tone arm 22 from the turntable 21, and specifically from a record 57 which is supported in a playing position on the turntable. The follower 51 is of angular form and includes a straight portion 58 and a bent portion 59, the portion 59 being inclined upwardly into the tone arm 22. The straight portion 58 is slidably supported in a sleeve member 61, which in turn is rotatably supported in a bearing block or bushing 62. The bushing 62 is formed with a shoulder 63 for seating on the wall or plate 20 and with a threaded extension 64 which projects through the plate 20; the tightening of the nut 66 about the extension 64 acting to hold the block 62 in a fixed position on the plate 20 in an obvious manner. Bent portion 59 is engageable with the upper side of the tone arm 22 which is pivoted at 67 to a supporting leg member 68 having an inwardly extending flange portion 69 formed at its lower end. The upper end of the sleeve 61 is formed with an outwardly extending flange or lip 71 which is adapted for engagement with the flange portion 69 as by welding or like means. It is thus seen that any angular or rotational movement of the sleeve 61 effects a corresponding angular movement of the tone arm 22 through the leg member 68.

The lower end of the sleeve 61 projects beyond the threaded extension 64 of the bushing 62, to provide for the mounting at such end of a rocker arm 72, the arm and sleeve being held together in frictional engagement by means of a holding screw 73 or like means. The free end of the arm 72 (Fig. 4) is pivotally connected at 74 in the end portion 76 of a selector link or lever arm 77, the end portion 76 being of sufficient width to also provide for the rotatable mounting therein of the cam follower 53 at a distance from the pivotal connection 74. Angular movement of the rocker arm 72 and hence of the sleeve 61 and tone arm 22, is effected by the movement of the cam follower 53 on the cam face 52, the follower 53 being guided in its movement by the groove 55. A longitudinally extending slot 79 formed in the end 78 of the lever arm 77 is adapted to slidably receive therein a pin

member 81 which is held in a flat plate or selector disc 82.

The disc 82 is mounted at the lower end of a shaft 83 as by welding or like means, the shaft 83 being rotatably supported in a supporting stand or shaft 84 for the edge of a stack of records 86, which are located vertically above the turntable 21 (Figs. 5 and 6). The stand 84 is adapted for seating on the cabinet plate 20 and is formed with a threaded extension 87 which extends through the plate 20, the stand 84 being secured to the plate 20 by a tightening of the nut 88 on the threaded extension 87. The upper end of the shaft 83 is pin connected at P to a supporting platform or shelf 89 for the records 86, the shelf 89 being rotatably supported on the upper end of the stand member 84. The records 86 are pressed downwardly on the shelf 89 by means of a retaining clamp 91 (Fig. 10) which is pivotally supported in a hollow post member 92 provided on the platform 89, the clamp portions 94A being positioned in corresponding notches or slots 92A oppositely formed in the top of the post 92 (Fig. 5). Retention of the clamp in the slots 92A is accomplished by a cap 92B which covers and frictionally engages the top of the post 92. Pressure on the clamp for holding the records 86 in stacked position is applied by a spring 93 which is connected at one end to the upset clamp portion 94, its opposite end 95 being connected to the shelf 89.

As is shown best in Fig. 1 the shelf 89 is of substantially rectangular form and is arranged in an offset position longitudinally relative to the stand member 84 to provide for unequal shelf lengths on opposite sides of the stand 84. When ten inch records are to be played the long length of the platform 89 supports the edge of the records, the platform being in the position indicated in dot-dash lines; when twelve inch records are to be played the short length of the platform supports the edge of the records, the platform being in the position indicated in full lines, the two positions being obtained by a 180 degree rotation of the platform 89 and hence of the shaft 83. The 180 degree rotation of the shaft 83 effects a movement of the end 78 of the selector arm 77 from one side of the shaft 83 to the other side of the shaft through the sliding action of the pin 81 in the slot 79 (Fig. 4). The rotational limits of the shelf 89 are defined by the engagement of the notches 80 formed in the selector disc 82 with the pin 75 in the spring tensioned pivotal indexing lever 85. When the record platform 89 is positioned for the playing of ten inch records the arm 77 is in the position indicated by the dot-dash lines. On 180 degree rotation of the shelf 89 to accommodate twelve inch records the arm 77 is moved to the position indicated by the full lines. The movement of the arm 77 provides for a movement of the rocker arm 72 and specifically the pivotal connection 74 thereof, relative to the cam follower 53, the position of which is practically unchanged by the movement of arm 77. The angular movement of the rocker arm 72 is directly controlling in the angular movement or swing of the tone arm 22, the movement of the rocker arm 72 downwardly to the left as seen in Fig. 4 providing for an initial starting position of the tone arm 22 on the record 51 to be played, at an increased distance out from the circumference of the turntable 21; the increase in distance being schematically illustrated by the tone arm positions in Fig. 4; the dotted lines representing the starting position of the tone arm 22 75 21, except for its centering engagement about

when the platform 89 is positioned to accommodate twelve inch records and the dot-dash lines indicating the starting position of the tone arm 22 when ten inch records are being played. It is thus seen that after adjustment of the platform 89 the operative engagement of the cam 52 with the roller 53 controls the angular movement or swing of the tone arm 22 and that the cam follower 51 as actuated by the cam 54 controls the lift of the tone arm 22, relative to the record being played.

The cam follower 56, which is operatively associated with the cam face 54 of the multiple cam 47, is rotatably mounted at one end of a crank arm 96 which is pivotally supported in a bearing member 97 suspended from the cabinet wall 20. The opposite end 98 of the crank arm 96 is provided with an adjusting screw 99 which is adapted to abuttingly engage the lower end of an operating member 101, which is slidably supported axially of the spindle or shaft 28 (Fig. 5). The spindle 28 is formed with an offset upper portion 102 to form a shoulder 103, the shoulder 103 acting as a center support for the stack of records 86 which are centered about the portion 102. A groove or mill slot 104 (Figs. 2 and 3) is formed in the shaft 28 at a position substantially opposite from the shoulder 103, the groove being of a sufficient depth to provide an opening 106 in the bottom thereof at the shoulder 103. A trigger or trip lever 107 is pivotally connected to the shaft 28 and is completely retractable within the groove 104 so that records from the stack 86 may be centered about the shaft without obstruction by the trip lever 107. The lower end of the lever is provided with an inclined side portion 108 which is adapted for slidable engagement with the upper end of the operating member 101, to effect a pivotal movement of the lever 107. The upper end of the lever 107 is formed with a projecting finger 109 which is moved through the opening 106 and over the shoulder 103 on pivotal movement of the arm 107 by the member 101, for a purpose to be later described. On retraction of the member 101 from its engagement with the side portion 108, as by the spring retained means 111, (Fig. 5), the finger 109 is removed from the opening 106 by the spring 112 which is arranged in compression between the lever 107 and the bottom of the groove 104.

The pivotal movement of the trip lever 107 by the operating member 101 provides for an engagement of the finger 109 with the lowermost or bottom record 86' at the central aperture 113 formed therein. Since the finger 109 is of a length to extend completely over the shoulder 103, the record 86' is pushed clear of the shoulder 103 and into centering engagement about the lower portion of the spindle 28; the spindle being of a diameter slightly less than the diameter of the aperture 113 in each of the records of the stack 86. Since the lever 107 is completely retractable within the groove 104 the record 86' is free to fall into a playing position on the turntable 21.

As is best illustrated in Fig. 5, the shoulder or center support 103 is of a depth commensurate with the extent or length of the support given the edges of the records by the supporting platform 89. The movement of the lowermost record 86' from the shoulder 103 is thus sufficient to effect a complete separation of the record 86' from the platform 89, so that the record 86' is entirely unsupported in its drop to the turntable 21, except for its centering engagement about

the spindle 28. The trigger or record releasing means 107 is thus operable to provide for a separation or release of a record 86' from a stack of unplayed records 86, by engaging the record at its immediate central portion at the aperture 113, which record portion is least effected by warping and is the same for all sized records. Since the finger 109 abuttingly engages the record 86' to provide for its separation from the remainder of the stack, the slight bending which might occur at the center of the record as a result of warpage, does not in any way decrease the operating efficiency of the record changing apparatus. The invention is thus equally adaptable for operation with warped records or with records of flat contour.

The pivotal movement of the releasing lever 107, as effected by the operating member 101 and the spring 112, is limited by the engagement of the shoulder or stop 114, formed at the top of the lever 107, with the walls of an eccentric cap member 116 which is rotatably mounted about the offset spindle portion 102. The cap or aligning member 116 is of a diameter substantially equal to that of the main body portion of the spindle 28 and is formed with an offset bore 117 to provide for its eccentric mounting on the offset portion 102. When a stack of records are to be located above the turntable 21 and about the portion 102, the cap member 116 is rotated until substantially its thinnest wall section is positioned at the shoulder 103. Since the diameter of the member 116 is substantially equal to the diameter of the apertures 113, the placement of the records 86 about the cap member 116 provides for an aligning of the record stack on the shoulder 103 the cap acting also to prevent any shifting of the stack during the release therefrom of the bottom record. A successive feeding of the records on the shoulder 103 with each dropping of the bottom record 86' on the turntable 21 is assured by the downward pressure effected on the stack 86 by the retaining clamp 91.

When all of the records have been played and it is desired to remove the records from the turntable 21, the member 116 is rotated until substantially its thickest wall section is positioned at the shoulder 103. This position of the cap member 116, as illustrated in Fig. 5, provides for a shaft or spindle 28 which is in peripheral alignment over its entire length, the thick wall section of the cap member 116 being of a thickness commensurate to the depth of the shoulder 103 and the thin wall section of the cap member 116 being of a section commensurate with the degree of offset of the portion 102 at the side opposite from the shoulder 103. Since the pivotal lever 107 is completely retractable within the groove 104 the shaft 28 is unobstructed over its entire length so that all of the records positioned on the turntable 21 may be removed at one time and in a stack from the spindle 28. It is understood, of course, that prior to the lifting of the records from the spindle the shelf 89 of the edge support 84 is rotated out of its engaging position with the records 86 and into a position with a longitudinal side facing the spindle 28. To facilitate the positioning of the cap member 116 to its operating positions on the portion 102 there is provided a pin 118 in the portion 102 which is adapted to ride in a slot 119 formed in the wall portion of the member 116, the ends of the slot 119 defining the limiting positions of rotational movement of the cap 116. A spring 121 arranged in compression between the top of the bore 117

and the top of the offset portion 102 acts to hold the cap 116 in its limiting positions.

The operation of the above described record-changing apparatus to effect an automatic changing of the records in the stack 86, is obtained through an electrical control circuit which is closed in response to a predetermined position of the tone arm on the record, such as 57, supported in playing position on the turntable 21. 5 The circuit, (Fig. 6A) is illustrated as being energized from a suitable electrical source through a transformer 125 and includes a main switch 122 for the motor 23, a solenoid 123 and a control switch 124A having switch arms 124, the control switch 124A being controlling in the energization of the solenoid 123. A reject button or switch 120 is arranged in parallel with the control switch 124A to provide for a separate closing of the circuit. The multiple cam 47 and its 10 associated cam followers are illustrated in Fig. 4 in the positions which they assume when the tone arm 22 is in a starting position on the record to be played; the record being indicated as a twelve inch record although it is to be understood that the operation is the same for either a ten or a twelve inch record. As the tone arm 22 moves inwardly across the record 57 toward the spindle 28 the rocker arm 72 is moved inwardly toward the shaft 42, the follower 53 moving freely in a widened portion of the guiding groove 55 during the entire playing of the record, and the follower 51 being in engagement with the low portion 50 of the cam face 49 (Figs. 4 and 9).

20 The rocker arm 72 is provided with a pair of spaced fingers 126 which are adapted to frictionally engage a switch plate 127 which is attached to the outer one of the contact arms 124. When the tone arm 22 is in partial traversal of the record 57 the fingers 126 frictionally engage the plate 127, but since the pressure exerted by the fingers 126 on the plate 127 is in a direction to maintain open the contact arms 124 the electrical control circuit is also maintained open. 25 However, when the record is completely traversed the tone arm is carried to an eccentric or spiral groove 128 (Fig. 1) at the center of the record, which provides for an oscillating movement of the tone arm. As the tone arm 22 is first moved outward in a direction away from the spindle 28 by its oscillating movement in the groove 128, the fingers 126 on rocker arm 72 are moved in a direction toward the shaft 42, which movement provides for a pulling inwardly of the plate 127 by the fingers 126 and a closing of the contact arms 124 to close the control circuit for the record changing apparatus.

30 The closing of the control circuit by the switch arms 124 provides for an energization of the solenoid 123 to actuate a pivotal armature 129. The armature 129 (Figs. 4 and 8), during the playing of a record 57 is pulled by a spring 134 into a position for supporting or holding a dog 131 above the serrated flange 46 of pulley 41, as shown in full and dotted lines in Fig. 4, the dog 131 being pivotally connected to the cam 47 and adapted for engagement with one of the serrations in the serrated flange 46. Actuation of the armature 129 by the solenoid 123 to its position shown by the dot-dash lines in Fig. 4 releases the dog 131 (Fig. 7) for engagement with the pulley 41. Since the pulley 41 is in continuous rotation, rotation of the cam 47 is obtained immediately upon the engagement of the dog 131 with the pulley 41. In the rotation of the cam

47 in a clockwise direction, as shown in Fig. 4, the cam face 49 acts first to operate the cam follower 51 to raise the tone arm 22 from the played record 57 prior to any outward swinging or angular movement of the tone arm towards the circumference of the turntable 21. After the arm 22 has been raised to clear the record 57 the cam follower 53 is engaged by the cam face 52 to effect a movement of the tone arm 22 outward from the spindle 28 toward the circumference of the record 57, the cam follower 51 continuing to ride on the high portion of the cam face 49 to maintain the arm 22 in a lifted position. When the tone arm 22 has been moved to its outermost position and completely off the face of the record 57, which position is indicated on the portion of the cam face 52 between the lines 132, the cam follower 55 is riding on the high portion of the cam face 54, which is indicated in Fig. 9, to provide for an actuation of the operating member 101 by the crank arm 96, the member 101 acting to move the pivotal lever 107 in a manner to release the bottom record 86' of the stack of records 86 from its supported position on the shoulder or center support 103 and platform or edge support 88. The record 86' is thus dropped into a playing position on the turntable 21 only after the tone arm 22 is completely removed from the face of the record which has been played. After the record 86' is in a playing position on the turntable 21 the cam face 52 provides for a movement of the tone arm inwardly toward the circumference of the record 86', the cam face 49 and cam follower 51 operating concurrently to provide for a lowering of the tone arm in operative engagement on the newly positioned record.

The dog 131 is pivotally movable in an aperture 133 formed in the cam 47 in a position near the end of the effective working portion of the cam face 52. The rotation of the cam 47 effects a disengagement of the fingers 126 with the plate 127, by moving the rocker arm 72 outwardly from the shaft 42, whereby to open the control circuit and to de-energize the solenoid 123 to release the armature 129. The armature is immediately pulled back into an engaging position with the dog 131 by the spring 134 so that as the cam 47 rotates, the dog 131 is brought back to its starting position where it is engaged by the armature 129 and lifted out of engagement with the serrated flange portion 46 of pulley 41, to immediately stop rotation of the cam 47. The record changing mechanism is thus conditioned for the playing of the new record positioned on the turntable 21, the entire record changing operation being completed by a single complete revolution of the cam 47. It is to be noted also that the record changing apparatus does not at any time contact or engage the musical grooves in the records whereby to reduce scratched records and consequently poor sound reproduction to a minimum.

In the event it is desired to change a record which is only partly played there is provided a reject button 128 (Fig. 1) which is operable to effect an immediate energization of the solenoid 123 independently of the relative positions of the contact arms 124, the solenoid actuating the armature 129 to release the dog 131 for engagement with the pulley 41. On rotation of the cam 47 the operation of the record changing mechanism is similar to that just described.

The modified form of the invention illustrated in Figs. 11 to 14, is adapted for the automatic

changing of a single sized record only and is employed with the usual turntable 136, and tone arm 137 which are arranged on a wall or frame means 138 of a phonograph or like machine; the tone arm being operatively associated with a sound box 139 (Fig. 13) having an amplifying tube 141. The turntable 136 (Fig. 11) is driven through friction gears 142 and 143 by a low voltage induction motor 144, and is rotatably mounted about a spindle or record centering member 146, which is mounted in the wall 138; the hub portion 147 of the turntable being provided with a pulley 148 which is in driving engagement with an idler pulley 149. The pulley 149 is mounted at the upper end of a countershaft 151 which is rotatably supported in a bearing block 162, the block 162 being suitably secured to the wall 138 as by welding or like means.

An idler pulley 153 is provided at the lower end of the countershaft 151, rocker arms 154 and 156, to be hereinafter fully described, being rotatably mounted about the shaft 151 between the bearing block 162 and the lower idler pulley 153. The pulley 153 is in driving engagement with a pulley 157 which is adapted for a direct driving connection with operating cams 158 and 159, the pulley 157 being secured at the lower end of a countershaft 161 which is rotatably supported in a bearing block 162, which in turn is mounted in the wall 138. The cams 158 and 159 are rotatably mounted for concurrent rotation about the shaft 161 and between the pulley 157 and bearing block 162. It is thus seen that the pulleys 149 and 153 mounted on the countershaft 151 act as reduction pulleys and that all of the pulleys 148, 149, 153 and 157 are continuously rotated during the operation of the motor 144.

The cam 158 is operable to provide for a lifting of the tone arm 137 from the record 163 being played and is operatively associated with a cam follower 164 which is rotatably mounted at the end of a lever 166 formed on rocker arm 154. The lever 167 of arm 154 is connected to one end of an actuating rod 168 between adjusting collars 169, the opposite end of the rod being pivotally connected to arm 171 of bell crank 172, which is pivotally mounted in a supporting bracket 173 suspended from the frame member 138. The crank arm 174 is in slidable engagement with an operating rod 176, the lower end of the rod being provided with an adjustable shoulder or collar member 177 which is adapted to abuttingly engage the crank arm 174. The rod 176 extends through a bore formed in a pivot member 178, which is mounted in the frame member 138, the upper end of the rod being adapted for engagement with the arm 179 of bell crank 181, which is pivoted in the tone arm 137. An arm 182 of bell crank 181 is in sliding engagement with the stylus end 183 of the tone arm, the portion 183 being pivotally connected to the main body portion 184 of the tone arm so as to be pivotally movable independently of such main portion. The tone arm 137 is rotatably mounted on the pivot member 178 and is rotatably supported on a spacer or collar 185 which is mounted on the member 178 and arranged between the arm 137 and the frame member 138.

With reference to Figs. 13 and 14 it is thus seen that a movement of the lever 166 by cam 158 outwardly from the shaft 161 effects a movement toward the left of lever 167, to provide for a downward movement of the bell crank 172 by

the actuating rod 168, the crank arm 174 engaging the collar 177 to pull down the rod 176, which in turn pulls down the crank arm 179 to effect a raising of the tone arm portion 183 by the crank arm 182.

The cam 159 is operable to provide for a swinging movement of the arm 137 outwardly from the center of the record 163, and for a releasing of the lowermost record 186' from the records 186 stacked above the turntable 136, to a playing position on the turntable. The cam 159 (Fig. 13) is operatively associated with rocker arm 156 which is formed with oppositely disposed levers 187 and 188, the lever 187 being provided with two free ends 189 and 191. The lever 188 is pivotally connected to a link 193, which in turn is pivotally connected to the tone arm 137. A pivotal movement or swing of the arm 137 is thus obtained by a movement of the rocker arm 156 by the cam 159.

A cam follower 192, adapted for rolling engagement with the cam 159, is rotatably mounted at the end 189 of lever 187. The end 191 is provided with a retaining or supporting member 193 which is formed with a projecting ear 194 having an aperture extending therethrough. The aperture in the ear 194 is adapted to receive one end of a connecting rod 196, such end being provided with an adjusting collar 197 which is adapted to abuttingly engage the ear 194. The opposite end of the rod 196 is pivotally connected to a bell crank 198, which in turn is pivotally connected to a bracket 199 suspended from the frame wall 138. (Fig. 12). The bell crank 198 is formed with three arms 201, 202, and 203, which are arranged substantially 90 degrees apart. The arm 203 is pivotally connected to an operating member or rod 204 which is slidably supported in the spindle or shaft 146, the upper end of rod 204 being adapted for slidable engagement with a releasing or trip lever 206. The shaft 146 is of substantially tubular form and is provided at its upper end with an offset portion 207 to form a shoulder 208 for supporting the center of the stack of records 186. The lever 206 is pivotally connected to the shaft 146 at the portion 207 which is suitably slotted to receive the lever 206 axially of the shaft 146, the lever 206 being completely retractable within the shaft 146. The lever 206 is provided with a projecting finger 209 which is adapted to be moved over the shoulder portion 208, the finger being of a length commensurate with the depth of the shoulder 208. Thus upon an upward movement of the rod 204 into sliding engagement with the lower end of the releasing lever 206, the finger 209 engages the bottom record 186', at the central aperture 210 formed therein, and pushes the record 186' completely clear of the shoulder 208 for centering engagement or alignment with that portion of the shaft 146 below the shoulder 208. Since the shaft 146 is entirely unobstructed over its length below the shoulder 208 the record 186' is permitted to fall into a playing position on the turntable 136.

The edge support 211 for the stack of records 186 (Fig. 12) includes a column or standard 212 having a supporting platform or shelf 213 and a record retaining clamp 214 pivotally connected near its upper end. The support given to the edge of the records 186 by the shelf 213 is of an extent corresponding to the depth of the shoulder 208 so that when the record 186' is kicked or pushed clear of the shoulder 208 by the releasing lever 206, the record 186' will also be entirely clear or separated from the platform

213. The lever 206 thus operates to effect a concurrent separation of the record 186' from its center support at 208 and its edge support at the platform 213. It is seen, therefore, that a movement of the lever 187 of rocker arm 156 in a direction outwardly from the shaft 161 effects a movement of the lever 196 toward the right, as shown in Fig. 12, which in turn provides for an upward movement of the operating rod 204 into sliding engagement with the lever 206 and an engagement between the finger 209 and the lowermost record 186', whereby to drop the record 186' into a playing position on the turntable 136.

The rod 204 is moved out of sliding engagement with the lever 206 by the spring 216 which is attached at one end to the crank arm 202 and at its other end (not shown) to a portion of the frame structure 138. The retraction of the arm 204 out of engaging position with the lever 206 is limited by the adjusting screw 220 which is positioned in the crank arm 201 and adapted for abutting engagement with the frame member 138. Movement of the lever 206 outwardly from the shaft 146 and specifically of the finger 209 into engagement with the bottom record 186' is limited by the stop member 215 formed at the shoulder 208. After disengagement of the rod 204 from the lever 206, the finger 209 is removed from the shoulder 208 by the action of the spring 217, which is arranged in compression between the lever 206 and the wall of the shaft portion 207, the return of the lever 206 to its starting position being limited by engagement of the lever with the wall portions 218.

The retaining member 193 at the end 191 of arm 187 is also provided with control arms or pins 221 and 222 which project outwardly therefrom for disposition on opposite sides of the pulley 157 and are adapted for selective contact with a dog or trip lever 223, which is pivotally connected to the pulley 157 at an aperture 224 formed in the pulley face. Oppositely extending fingers 226, 227 are arranged at opposite ends of the dog hub member 228, the finger 227 being adapted for abutting engagement with a depending ear 229 formed on the lower side of the cam member 159, and the finger 226 being positioned for selective engagement with the arms 221 and 222, to control the engagement of the finger 227 with the ear member 229. The arm 221 is of straight form and relatively short and is adapted to contact or engage the upper side of the finger 226 on a movement of the lever 187 inwardly toward the shaft 161. The arm 222 is relatively long and of substantially U-shaped configuration, the arm end 231 being adapted to engage the lower side of the finger 226 on a movement of the lever 187 outwardly from the shaft 161, the dog 228 during the normal playing of a record 163 passing within the U-shape of arm 222 and out of engagement with the arm 221 and end 231 of arm 222.

The operation of the embodiment illustrated in Figs. 11 to 14, is best understood from Fig. 13. At the start of playing a record 163, with the tone arm 137 positioned near the circumference of such record, the dog 223 is in an unengaged position with the ear member 229 and out of engaging contact with arms 221 and 222. The cams 158 and 159 are thus in a neutral position with the cam portion 225 of cam 159 near the roller 192 and the cam portion 230 of cam 158 near the roller 164, the rollers 164 and 192 being relatively free of their respective cams to permit a free movement of the tone arm in its traverse of the

record 163. As the tone arm 137 approaches the center of the record 163 the rocker arm 156 is actuated by the tone arm, through the lever 183, to move the lever 187 inwardly toward the shaft 161. The inward movement of the lever 187 in turn moves cam follower 192 in toward the low face 225A of the cam 159, and the controlling arms 221 and 222 inwardly over opposite faces of the pulley 157. During the playing of a record, therefore, the cams 158 and 159 are not rotated and the rocker arm 156 is moved relative to the cam 159 by movement of the tone arm 137 across the record 163. When playing of the record 163 is completed the tone arm is carried toward the center of the record by the usual spiral or eccentric groove 232 (Fig. 11), which movement of the tone arm 137 acts to provide for an engagement of control arm or pin 221 with the dog finger 226 to move the dog finger 227 into engagement with the cam ear 229. Immediately upon engagement of the finger 227 with the ear 229 the cams 158 and 159 are set into a counter-clockwise rotation as viewed in Fig. 13, the cams 158 and 159 and their associated rocker arms 154 and 156, respectively, being shown in the positions which they assume at the start of operation of the record-changing apparatus.

In the sequence of operation of the record-changing apparatus, the cam 158 operates first to provide for a raising of the tone arm 137 from the record 163 prior to any outward swinging of the arm 137 by the action of the cam 159, the follower 192, at the start of operation, being at the low face 225A of the cam 159 and the follower 164 being rapidly moved to the high face of cam 158. The contour of the cam 158 is such as to maintain the tone arm 137 in a raised position from the record 163 during substantially the entire operation of the record-changing mechanism. After the tone arm 137 has been lifted from the record 163 the cam 159 operates to move the tone arm outwardly from the spindle 146 toward the circumference of the record 163, this action continuing until the tone arm is entirely clear of the record, this position of the arm occurring when the cam portion included between the lines 236 is in engagement with the cam follower 192; which cam portion represents the high side or face of the cam 159. As this portion of the cam engages the cam follower 192, engagement occurs between the collar 197 and the ear 194 to provide for an actuation of the operating arm 204 to operate the record release lever 206 in the manner previously described. The record 163, therefore, is dropped into a playing position on the record 163 only after the arm 137 is completely clear of the face of the record 163. With the released record in a playing position, the tone arm is moved inwardly to the circumference of the record concurrently with a lowering thereof into operative engagement with such record by the cam 158. This inward movement of the tone arm 137 to its starting position for playing the record is accomplished by the action of the spring 216 on the pivoted bell crank 198. By virtue of the rod 196 being pivotally connected at one end of the arm 202 of the bell crank and at its opposite end to the end 191 of the lever 187, the spring 216 serves to pull the cam follower 192 at the lever end 189, inwardly toward the shaft 161 and into following engagement with the cam 159. During the rotation of the cam 159 the lever 187 is moved away from the shaft 161 which movement carries control arm 221 out of an engaging position and the

portion 231 of arm 222 into an engaging position with the lower side of the tripping finger 226. Thus when the record-changing operation is completed and the dog 223 is returned substantially to its initial starting position, the finger 226 engages the portion 231 of pin 222 to disengage finger 227 from the cam ear 229, whereby to stop the rotation of the cams 158 and 159. The cams 158 and 159 are thus returned to their neutral positions and the record-changing mechanism is conditioned for the playing of a new record; the record changing operation being accomplished during substantially one complete revolution of the cams 158 and 159. Since the pivotal movement of the bell crank 198 by the spring 216 is limited by the adjusting screw 220, the cam follower 192, when the cam 159 is in its neutral position, is retained in a floating position out of engagement with the cam 159 and between the cam portions 225 and 225A. The lever 187, therefore, is free to be moved inwardly toward the cam portion 225A by the transverse of the tone arm 137 across the record being played, the bell crank 198 remaining in its stop position because of the slideable connection of the rod 196 with the ear 194 on member 193. Thus, on completion of a record, the follower 192 is adjacent the cam portion 225A, so that the rocker arm 156 is actuated substantially immediately on a starting of rotation of the cam 159.

The invention is thus seen to provide for a record changing mechanism for a phonograph or like machine, which is of simple construction, positive in operation, readily adaptable for the accommodation of either ten or twelve inch records, and which consists of but few parts requiring adjustment. The mechanism is substantially completely located below the turntable and out of sight to provide for a neat appearance of the playing machine. The stationary turntable spindle is adapted to provide a center support for the plurality of records stacked above the turntable and is provided with means located on the inside thereof which are operable to effect a successive release of the stacked records 40 into a playing position on the turntable. The release of successive records by engagement of the releasing mechanism with the center portion of the record rather than the circumference thereof, provides for a positive operation of the releasing mechanism for warped records as well as for substantially flat records. The provision of an eccentric cap member rotatably mounted on the offset top portion of the turntable spindle provides for a positive alignment of the stacked records on the center support so that successive records are similarly handled by the tripping or releasing lever which is located within the turntable spindle. The rotation of the eccentric means to provide a spindle which is in peripheral alignment over its entire length provides for an unobstructed removal at one time of a complete stack of records from the turntable.

It is to be understood that only preferred embodiments of the present invention have been illustrated and described herein and that modifications and alterations in the invention can be made which are within the full intended scope of the invention as defined by the appended claims.

I claim:

1. In a sound reproducing machine adapted to play a plurality of disc records in succession having a rotary turntable and a plurality of unplayed

records stacked above said turntable, the combination of a stationary spindle extending upwardly from a point below the top surface of said turntable, said spindle having an off-set upper portion forming a shoulder thereon at the bottom of said off-set portion and being hollow below the shoulder, the unplayed records being stacked about said off-set portion with said shoulder acting as a center support for said stack of records, movable means having a body portion within said spindle and an ejector portion thereon movable with reference to the shoulder to move the lowermost record of said stack of records off of said shoulder for centering engagement about the spindle below said shoulder so that said record drops into a playing position on said turntable, means operatively connected to said body portion at the lower end thereof to move the ejector portion outwardly to drop a record, and means mounting said off-set portion above said supporting shoulder, and said off-set portion being rotatable to a position in alignment with the spindle below said shoulder so that the stack of records after playing may all be removed simultaneously from said turntable upwardly past the shoulder, the ejector portion, and the off-set portion.

2. The combination with a rotary turntable for a sound reproducing machine, of a centering unit stationary relative to said turntable and extending upwardly from a position below the top surface thereof, said centering unit including a bottom portion extending upwardly from said turntable and an eccentric rotary portion at the top, with a shoulder on said bottom portion intermediate said bottom portion and the eccentric portion, means on said bottom portion supporting the eccentric portion for rotation into and out of axial alignment with said bottom portion, said eccentric portion when out of axial alignment with said bottom portion being adapted to center a stack of records thereon for support on said shoulder, said eccentric portion being rotatable to a position of axial alignment with the bottom portion to cover said shoulder so that the stack of played records can be moved at one time upwardly over the bottom portion and said eccentric portion for complete renewal from said centering unit.

3. The combination with a rotary turntable for a sound reproducing machine, of means for supporting a plurality of records above said turntable and guiding said records collectively or individually to and from said turntable, said means including a stationary centering member extending upwardly from a point below the top surface of the turntable having a bottom portion in vertical alignment with the axial center of said turntable and a top portion off-set from said bottom portion and a horizontal shoulder on said bottom portion intermediate said top and bottom portion, a sleeve movably mounted on said off-set portion, means on said off-set portion mounting said sleeve for movement into and out of substantially peripheral alignment with said bottom portion, said supporting means also including a stationary support spaced radially from said centering member having a ledge adjacent the top thereof, with said centering member shoulder and said support ledge supporting a plurality of records thereon when said sleeve is out of peripheral alignment with said bottom portion, and means individually engaging each of said stacked records in succession and moving the engaged record from said shoulder and said

ledge so that it will drop to said turntable while guided by said bottom portion.

4. The combination with a rotary turntable for a sound reproducing machine, of means for supporting a plurality of records above said turntable and guiding said records collectively or individually to and from said turntable, said means including a stationary member centered relative to said turntable and extending upwardly from a point below the top surface thereof, said member having an off-set top portion of reduced section and a shoulder at the bottom of said top portion, said records being positioned about the top portion with the lowermost record supported directly on said shoulder, an eccentric member rotatably mounted on said top portion and normally positioned out of peripheral alignment with the bottom portion of said stationary member to center said records for support on said shoulder, and means for engaging in succession the lowermost one of said records and moving the engaged record from said shoulder so that it will drop about said bottom portion into a playing position on said turntable, with said records being removable in a stacked relation from said turntable when said eccentric member is rotated into peripheral alignment with said bottom portion.

5. The combination with a rotary turntable for record playing apparatus, of means for supporting a plurality of records above said turntable and dropping the same individually thereon including a stationary hollow spindle at the center of the turntable extending upwardly from a point below the top surface thereof, said spindle having an off-set portion of reduced diameter at the top with a shoulder at the bottom of said off-set portion, said records being positioned about said off-set portion with the lowermost record supported directly on said shoulder, an eccentric sleeve rotatably mounted on said off-set portion and above said shoulder for aligning said records into a supported position on said shoulder, said sleeve and bottom portion of the spindle being of substantially equal diameters, a pivoted ejector lever completely retractable within said spindle, axis means on said spindle below the shoulder pivotally supporting said lever, said lever having an ejector portion pivotally movable outwardly from said spindle and over said shoulder, said lever in its retracted position being in alignment with said eccentric sleeve to permit movement of said records downwardly on said shoulder, reciprocal means within said spindle extending upwardly from below the turntable engaging said lever and pivotally moving said ejector portion over said shoulder to push the lowermost record laterally therefrom so that it drops about the bottom of the spindle into a playing position on the turntable, and means below said turntable operatively connected with said reciprocal means to reciprocate the latter and move said lever, said eccentric sleeve being rotatable into peripheral alignment with the bottom of the spindle to cover said shoulder so that all of the records dropped on the turntable can be removed at one time therefrom by lifting them upwardly over the spindle.

6. The combination with a rotary turntable for a sound reproducing machine, of a centering unit for a stack of records stationary relative to said turntable and supported below the top surface of said turntable, said centering unit including a hollow bottom portion extending upwardly from said turntable, an eccentric portion at the top maintained at all times as a unit with

said bottom portion, with a record support shoulder at the top of said bottom portion and below the eccentric portion of said centering unit, record ejector means having a portion movable within the hollow bottom portion and a portion at the support shoulder for ejecting records therefrom to the turntable, means in said bottom portion supporting said eccentric portion for manual movement into and out of axial alignment with said bottom portion, said eccentric portion when out of axial alignment with said bottom portion centering a stack of records supported on said shoulder, said eccentric portion when in axial alignment with said bottom portion facilitating the removal of a stack of records upwardly from said turntable over said two portions for complete removal from the centering unit, and with said eccentric portion and bottom portion normally being stationary relative to one another during the rotation of the turntable in the reproduction of a record.

7. In record changer apparatus having a turntable, a tone arm adapted to play records on said turntable of at least two different diameters, and said apparatus adapted to support records of such different diameters at a center support position and an adjustable edge support position,

said apparatus including in combination a center support means including a hollow post maintained normally in the same position and having a shelf thereon intermediate the top and bottom thereof, an edge support means including a stationary hollow post spaced from said center support means and having a shelf for edge support of the records, and ejector means on one of said support means having a movable ejector portion 5 above the shelf of said support means and operating means within the hollow post acting on said ejector means for operating the same, with said operating means being movable on a line substantially centrally and axially of said post 10 to operate said ejector means, with said ejector means being movable to move a record from both shelves to a position where it will drop over the center post to the turntable, with said edge support means including a shaft extending through said hollow post having said edge support shelf at one end thereof adapted to be manually pivoted to at least two different positions, and positioning means at the other end adapted to be releasably positioned upon manual movement of said shelf to a position corresponding to the diameter of the record being accommodated.

VAUGHN BUTLER.
